WARDROBE OR LOCKER

Frank Albach and George R. Chervenka, St. Louis,
Mo., assignors to Fred Medart Manufacturing
Company, St. Louis, Mo., a corporation of
Missouri

Application December 3, 1938, Serial No. 243,758

1 Claim. (Cl. 20—16)

This invention relates generally to storage lockers or wardrobes especially, though not exclusively, adapted for use in schools, factories, offices, public buildings, and the like and, more particularly, to certain new and useful improvements in storage lockers or wardrobes of the multiple compartment type.

In such lockers or wardrobes, each compartment is usually separately equipped with individual doors. In the present instance, such doors are of folding jack-knife type, and our present invention has for its primary object the provision upon the wardrobe or locker of readily constructed, easily and inexpensively installed and maintained, and conveniently operable means or mechanism for simultaneously opening and closing the folding doors of the several compartments.

And with the above and other objects in view, our invention resides in the novel features of form, construction, arrangement, and combination of parts presently described and pointed out in the claim.

In the accompanying drawings (3 Sheets)—

Figure 1 is a perspective view of a multiple-compartment locker or wardrobe equipped with folding door opening and closing mechanism of our present invention;

Figure 2 is an enlarged fragmentary perspective view of the locker or wardrobe, showing from the interior of a compartment of the locker the compartment folding door and the unison opening and closing mechanism;

Figure 3 is an enlarged fragmentary perspective view of an auxiliary resilient or yielding member forming part of the door-opening and closing mechanism;

Figures 4 and 5 are fragmentary horizontal or cross-sectional views of the compartment folding doors, taken approximately along the line 4—4, Figure 2, respectively illustrating the folding door in fully and partially closed position;

Figure 6 is an enlarged fragmentary vertical sectional view of a compartment door-section, taken approximately along the line 6—6, Figure 2;

Figure 7 is a fragmentary horizontal or cross-sectional view of a compartment door-section, taken approximately along the line 7—7, Figure 6;

Figure 8 is an enlarged fragmentary horizontal sectional view of the locker, taken approximately along the line 8—8, Figure 1;

Figure 9 is an enlarged fragmentary vertical sectional view of a compartment door-section, taken approximately along the line 9—9, Figure 2; and

Figures 10, 11, and 12 are enlarged fragmentary horizontal sectional views of the locker, taken approximately along the line 10—10, Figure 1,

illustrating a plurality of the compartment folding-doors in fully closed, partially closed, and fully opened positions, respectively.

Referring now in more detail and by reference characters to the drawings, which illustrate a preferred embodiment of our present invention, the present wardrobe A is preferably built up of and comprises a desired plurality of like preferably sheet metal rectilinear sections or compartments a, each including a top wall 1, opposed side walls 2, 2, a rear wall 3, and a bottom wall 4, the several like sections or compartments a being disposed, and bolted or otherwise secured together, in side-wall contiguous formation, as best seen in Figure 1.

Each of the locker compartments or sections a is formed with a front door-opening 5 marginally bounded by a pair of opposed parallel vertical stile members 6, 7, and opposed upper and lower parallel horizontal rails 8, 9, respectively, the latter being provided with longitudinally extending channels 10, 11, preferably of U-section, presented inwardly in opposed relation.

Swingably mounted along a side margin upon the stile 7 by means of suitable vertically spaced hinges 12, is a door-section d also constructed preferably of sheet metal and preferably sized to extend, when in closed position, across somewhat less than one-half of the front door-opening 5.

Hingedly mounted on the opposite or relatively free margin of the door-section d by means of vertically spaced hinges 13, is a second or companion door-section d' sized for extending, when closed, across the remainder of the door-opening 5 in the formation with section d of a complete closure for said opening 5, the door-section d' being provided at its remote or free corners with upwardly and downwardly presented studs or posts 14, 15, respectively, journaled upon which for movement in the respective ways or channels 10, 11, are suitable rollers 16, as best seen in Figures 2 and 9.

Welded or otherwise fixed at an arm 17 upon the inner face of the door-section d', is an operator lever in the form of a bell-crank c having its opposite arm 18 inwardly extending horizontally preferably at right angles to the plane of the door-section d' and pivotally provided at its free inner end with a connector-member 19 suitably apertured for receiving an operating rod or bar 20. A suitable locking set-screw 21 is threaded in the connector 19 for engaging the rod or bar 20 for securing the same adjustably to the operator c, as best seen in Figure 2 and for purposes presently more fully appearing.

The doors of the several units or compartments a of the particular locker A are thus of folding so-called jack-knife type, and it will be understood that each of the door-sections d' of

the several compartments or units *a* of the wardrobe or locker A is in like manner equipped with way-engaging rollers 16 and with an operator-arm *c* similarly attached to the link 20, which latter is of an overall length commensurate with the width of the several compartments *a* of the locker, as best seen in Figure 1.

Each of the door-sections *d*, *d'*, of the several locker-compartments is suitably marginally flanged, as at 22, 23, for attractive stile-engagement when closed, and preferably each door-section *d'* is provided in its flange 22 with an aperture 24 for loosely or freely accommodating a push-pin 25 fixed at an end on the free end *e* of a leaf-spring 26 at its other end riveted or otherwise secured upon the inwardly presented face of the particular door-flange 22, all as best seen in Figure 3 and for purposes presently more fully appearing.

20 By reference to Figure 12, it will be observed that the door-section *d'* of each unit *a* is of somewhat greater width than its companion door-section *d* and is provided longitudinally with a rib or flute 27 spaced inwardly from its hinged margin a distance substantially equal to the difference between the widths of the companion door-sections *d*, *d'*, for giving the two companion sections *d*, *d'*, of each compartment door a more or less balanced appearance when the same are in closurewise position across the door-opening 5.

For present descriptive purposes, one of the end compartments, as *a'*, will be designated the master unit of the locker A, and it will be further observed, by reference to Figure 1, that the larger door-section *d'* of the master locker unit *a'* is provided marginally with handles 28, 29, for purposes presently appearing.

The door-section *d'* of unit *a'* is also provided adjacent its upper margin with a conventional type of lock-member 30 having a movable bolt 31 for engagement with the upper stile 8 of the door-opening 5 for releasably retaining the door in closed position.

Similarly, the door-section *d* associated with or companion to the door-section *d'* of the master unit *a'* is provided with an upwardly extending stop member 32 positioned for abutting engagement with the forwardly presented face of the rear flange 18' of the channel 10, the latter being provided in its forward flange 10" with a slot 33 for permitting the stop member 32 to move forwardly upon outward swinging movement of the door-section *d'*, all as best seen in Figures 6 and 7. While not here specifically shown, it will be understood that each door-section *d'* of the locker A and each compartment-channel 10 may be similarly constructed for limiting door-movement to closed position.

In use and operation, the lock 30 in the "master" unit *a'* is turned, actuating the bolt 31 out of retentive engagement with the rear flange 18' of the upper rail or channel 10, thereby unlocking or releasing the several doors of the locker for opening movement. Initial outward pull exerted on the master door-section *d'* through the handles 28, 29, will cause the several sets of rod-connected door-sections to swingably shift out of a line of dead-center, such opening pull upon the several folding doors being yieldingly augmented by the pins 25. Thereupon, on further pull exerted through the handles 28, 29, the master door-section *d'* may be readily manipulated through the intermediate position shown in Figure 11

ultimately to fully opened position, as shown in Figure 12.

Now, as the master door-section *d'* is so swung or shifted to full open position, its rollers 6 will move or roll in the channels or ways 10, 11, causing the companion master sections *d*, *d'*, to move through a defined relatively angular path.

Meanwhile, on such movement of the master door-sections *d*, *d'*, the master L-shaped operator or bell-crank *c* will be swung about an angle 10 of 90° and at the same time shifted sidewardly. The operator rod or bar 20 will thereby be shifted longitudinally and each operator *c* correspondingly swung and shifted, thus transmitting simultaneously similar door-opening movement 15 through like defined angular paths to the roller-equipped companion door-sections *d*, *d'*, of each of the several compartments or units *a* of the locker, as best seen in Figures 10, 11, and 12.

By performing the same operations in reverse 20 sequence, the companion jack-knife connected sections of the doors of the several compartments of the locker may be readily simultaneously swung to closed position. In swinging to such position, however, the several push-pins 25 are yieldingly depressed, such pins 25 subsequently and so long as the respective sets of door-sections *d*, *d'*, are togglewise on a line of dead center functioning through pressure engagement with the fixed stiles 6 in yieldingly retaining the several folding doors 30 of the structure in fully closed position.

Thus conveniently and easily the companion sections of the doors of the several locker compartments may be simultaneously opened and closed, the actuating mechanism being of simple and inexpensive, but exceedingly efficient, structure.

It should be understood that changes and modifications in the form, construction, arrangement, and combination of the several parts of the locker 40 or wardrobe may be made and substituted for those herein shown and described without departing from the nature and principle of our invention.

Having thus described our invention, what we 45 claim and desire to secure by Letters Patent is—

A locker structure comprising a plurality of separate compartments each having a door opening flanked by an upright stile, a plurality of sets of upstanding folding doors of jack-knife type 50 for closing said respective openings, each of said sets including a first section hinged at a side margin to said stile and a second section hinged at a side margin to the free margin of the first section, trackwise extending upon the locker structure at the top and bottom and in parallel relation to the plane of each respective opening, members projecting from and at the free margin only of the second section of each of said sets 60 movable in said trackways for defining the movement of the second sections at their respective free margins in paths parallel with the plane of said openings, the movement of the connected margins of the sections of each of said sets being 65 arcwise with respect to the hinge-mounting of the first section thereof and wholly outwardly of the locker structure, and means including an elongated rod and respective bell-crank levers connecting the rod with the free margin of the second section of each of said sets for opening and closing the several sets of doors in unison.
